UNITED STATES PATENT OFFICE.

THEODORE A. WOLTERS, OF NEW YORK, N. Y., ASSIGNOR TO SANITARY BEVERAGE MIXER CO., INC., OF NEW YORK, N. Y., A CORPORATION OF NEW YORK.

BEVERAGE MIXER.

Application filed January 14, 1922. Serial No. 529,133.

To all whom it may concern:

Be it known that I, THEODORE A. WOLTERS, a resident of New York city, county and State of New York, and a citizen of the 5 United States of America, have invented certain new and useful Improvements in Beverage Mixers, of which the following is a specification.

This invention relates to improvements in 10 stirring or mixing devices, particularly for beverages, one of the objects of the invention being to provide an electrically operated mixing device; the operation of which is controlled by the positioning of the glass, 15 which contains the beverage to be mixed, relative to the mixing device. A further object of my invention is to provide a mixing device arranged so that a glass cannot be removed from the device until the mixing 20 spindle has been entirely lifted out of the glass. Further features of improvement will be pointed out in the description which follows.

I will now proceed to describe my invention in detail, the novel features of which I 25 will point out in the appended claims, reference being had to the accompanying drawing, forming part hereof, wherein:—

Fig. 1 is a vertical sectional view of my 30 improved device, partly in elevation;

Fig. 2 is a fragmentary plan view of the 35 brake mechanism, other parts being omitted;

Fig. 3 is an enlarged sectional plan view, the section being taken on line 3—3 in 40 Fig. 1;

Fig. 4 is a detail view of the switch mechanism; and

Fig. 5 is a sectional view, the section being taken on a line 5—5 in Fig. 2, the wedge 45 block being illustrated in elevation.

As one of the objects of my invention is to provide a sanitary mixer, I provide a standard 6 which is designed to receive a glass 7 and to protect or cover the open end 45 of the glass while the beverage therein is being mixed. The stand 6 is provided with a cover-plate consisting of a fixed part 8 and a removable part 9 which hangs upon the flange 10 of the neck 11 suspended from the 50 motor 12 which is also attached to the standard 6. When the glass 7 is placed in position, it will be slipped under the cover plate. At any time the removable member 9 of the cover can be taken off, should it be desirable 55 to inspect the contents of the glass while

the contents is being mixed. The mixing element consists of a spindle 13 provided with a spiral groove 14 which acts as a thread. The spindle 13 is carried by and passes loosely through the core 15 of the 60 motor armature 16 and is movable longitudinally of the said core. In this instance, the core 15 carries a head 17 having a pin 18 to engage the spiral groove 14. The lower end of spindle 13 carries an agitating device 65 19 of any suitable or desirable design. To the upper end of the core 17, I secure a hub 20 carrying a disk 21 having an annular flange 22 to act as a brake drum which acts in cooperation with brake shoes 23 and 24 70 pivoted together and to the member 25 of standard 6 at 26. The hub 20 yieldably supports a clutch sleeve 27 connected to said hub by a spring 28. One end of spring 28 is connected to sleeve 27 at 29, the other end of 75 said spring being connected to disk 21 at 30. To the upper end of spindle 13, I secure a weight 31 having an inclined surface 32 to match the inclined end 33 of clutch sleeve 27. In the circuit for motor 12 is included 80 a switch mechanism 34 consisting of contacts 35 and 36 carried by a block 37 of insulating material and a circuit-closer 38. The movement of the circuit closer is controlled (in this instance) by the movement of brake- 85 shoe 24 which carries an extension 39 supporting a bracket 40 which in turn carries a roller 41 which is designed to coact with the cam portion 42 of the circuit-closer 37. When the brake shoes 23 and 24 are forced 90 apart, roller 41 will be moved to the left in Fig. 4, or from the dotted to the full line position which will cause said roller to contact with cam surface 42 and force the circuit closer downwardly, whereby the pro- 95 jection 43 on said circuit closer will enter the gap between contacts 35 and 36 and close the circuit for the motor 12. The above mentioned action will take place when a glass is placed in mixing position relative to 100 spindle 14. The shoes 23 and 24 will be forced apart by the wedge portion 44 on a block 45 secured to the upper end of a vertically movable post 46 which is actuated upwardly when a glass is placed in position, 105 but drops when a glass is removed. When a glass is placed in position, it raises the outer end of a pivoted arm 47 upon which post 46 rests. When arm 47 is raised, block 45 will rise, causing its wedge 44 to separate 110

the shoes 23 and 24, thereby releasing the drum on core 15. The motor will now start to operate, because the circuit for the motor will close when said brake shoes are separated. It will be understood that when a glass is to be inserted or withdrawn, the spindle 13 will be in its uppermost position, indicated by dotted lines in Fig. 1. The spindle 13 will return to its normal or uppermost position when the motor is stopped automatically, as will be described later. Fig. 1 illustrates the spindle 13 in mixing position and nearly in its lowermost position.

To prevent the glass 7 from being withdrawn to an extent that would cause it to strike spindle 13, after the contents of the glass has been mixed and the motor stopped by moving the glass away from the switch 20 actuating arm 47, I provide a stop 48 pivoted at 49 to the standard 6, said stop being normally held in a vertical position by a spring 50. When the glass 7 is in mixing position, the free end or point 51 of the stop 48 will be located below the upper edge 52 of the glass; hence, should an attempt be made to withdraw the glass, it would strike stop 48 and further outward movement will be checked. Movement of the stop, to release the glass, is prevented by a latch 53 pivoted at 54 to the fixed portion 8 of the cover. The longer arm of the latch 53 projects toward spindle 13 and the end thereof is positioned at the path of vertical movement of the mixing element 19 which has an inclined upper wall 19^a. The latch 53 is actuated by gravity, in one direction, and by the upward movement of the mixer 19, in the opposite direction. Normally the spindle 13 will be in its uppermost position (see dotted lines Fig. 1), at which time a glass can be placed in mixing position or removed therefrom. When spindle 13 is in its uppermost position, latch 53 will be positioned, as indicated by dotted lines in Fig. 1, and switch arm 47 will also be in the position indicated by dotted lines.

To operate the device, a glass, containing elements to be mixed, will be slipped under the cover upon the base plate 55 and moved toward the left in Fig. 1. Before the glass reaches its final position under arm 47, it will strike the stop 48 and move its lower end to the left until the upper edge of the glass clears said edge, after which spring 50 will force the stop to full line position, Fig. 1. When the glass reaches its final position, switch arm 47 will be raised, thereby spreading the brake shoes 23 and 24 and also closing the circuit for the motor 12 which will now start and operate anti-clockwise. As the spiral groove 14 is right handed, the spindle 13 will move downwardly, the weight 31 acting as a drag to cause the spindle to lag; hence, said spindle

will be forced downwardly and will not rotate. As soon as the spindle has moved downwardly slightly, latch 53 will move to locking position, thereby preventing movement to the right, in Fig. 1 upon the part 70 of the stop 48; hence, the glass cannot be removed. It will be noted that latch 48 is controlled entirely by the spindle 13 and cannot be operated exteriorly of the standard, as it is enclosed by the fixed portion 75 8 of the cover. The spindle 13 will move downwardly until weight 31, at the top thereof, comes in contact with sleeve 27, after which the spindle will rotate anti-clockwise with the motor. After the contents of the glass have been mixed, the glass will be pulled away from arm 47, allowing said arm and block 45 to drop, thereby allowing spring 56 to move the shoes 23 and 24 into contact with the brake drum 22 80 and as the circuit for the motor will be broken by the contracting movement of the brake-shoes, the motor will stop. After the motor stops, the spindle 13 will continue to rotate anti-clockwise and hence will move 90 to normal or dotted line position, thereby releasing latch 53, after which the glass can be removed. It will be apparent that a glass cannot be removed until the spindle has reached its uppermost position, in which 95 position the mixer 19 will clear edge 52 of the glass. The resilient elements or arms 57 and 58 act as a brake to stop the spindle just before the lower end of the groove 14 reaches pin 18. The clutch elements 31 and 27, together with the clutch spring 28, act to connect the spindle and motor when member 31 contacts with member 27. To prevent the sudden starting of the spindle, in a rotary direction, is the function of the 100 spring 28, which will yield and cause the connection to be gradual.

What I desire to secure by Letters Patent is:—

1. In a beverage mixer, a support for a 110 receptacle, a mixing device movable into and out of said receptacle, and means controlled by the movement of the mixing device to prevent withdrawal of the receptacle from its support until the mixing device has been 115 moved out of the receptacles.

2. In a beverage mixer, a support for a receptacle, a mixing device movable into and out of said receptacle, a movable stop carried by the support arranged to project into 120 the receptacle, and means controlled by the movement of the spindle to lock the stop against movement.

3. In a beverage mixer, a support for a receptacle, a mixing device movable into 125 and out of said receptacle, a stop pivotally connected to the support arranged to project into the receptacle, and a latch controlled by the movement of the mixing device to lock said stop against movement. 130

4. In a beverage mixer, a motor driven mixing device, means to retain a receptacle adjacent thereto, means to lock the receptacle in position, and means to automatically release the locking means after a mixing operation has been completed.
5. The combination of a support, a spindle carried thereby, means to rotate the support, means to move the spindle longitudinally of its support while said support is rotating, and means to cause said spindle to return to its normal position by the force imparted thereto while the support is rotating, when said support comes to rest.
10. In a mixing device, a rotatable carrier, a threaded spindle supported by the carrier and rotatable therewith, means carried by the carrier to engage the threads on said spindle adapted to cause said spindle to lag when the carrier is rotated, whereby said spindle will be moved longitudinally of its carrier after the carrier has been placed in motion, and means carried by the spindle to contact with the carrier, when said spindle has been moved longitudinally of its carrier to its full extent, whereby said spindle will be rotated by the rotation of the carrier, said spindle being arranged to move back to its normal position by the force imparted to it, 30 while the carrier is rotating, after the carrier comes to rest.
15. In a mixing device, a motor, a spindle actuated thereby, a support for the spindle, means to move the spindle longitudinally of its support while the motor is operating, means to rotatably connect the motor and spindle when said spindle reaches the end of its longitudinal stroke, and means to cause the spindle to return to its normal position, by force imparted to it by the motor while operating, when the motor comes to rest.
20. In a mixing device, a rotatable carrier, a threaded spindle carried thereby but adapted to rotate therein, means carried by the carrier to engage the thread thereon, a weight carried by the spindle to cause same to lag when the carrier is rotated whereby said spindle will be moved longitudinally of the carrier after the carrier has been placed in motion, means to connect said spindle and rotatable carrier, when said carrier reaches the end of its stroke, whereby said spindle will rotate with said carrier, 50 the thread engaging means on the rotatable carrier being arranged to cause the spindle to return to its normal position, by force imparted to it while rotating, after the carrier comes to rest.
25. In a mixing device, a motor, a circuit therefor, a brake drum carried by the motor, a shoe normally engaging said drum, a circuit-closer adjacent the shoe included in said circuit, means carried by the shoe to operate placing of a receptacle in mixing position, relative to the moving device, arranged to move the brake shoe away from the drum, thereby also operating the circuit-closer and closing the circuit for the motor, and means to lock the receptacle in mixing position.
30. In a mixing device, a motor, a circuit therefor, a brake drum carried by the motor, a shoe normally engaging said drum, a circuit-closer adjacent the shoe included in said circuit, means carried by the shoe to operate the circuit-closer, means operable by the placing of a receptacle in mixing position, relative to the moving device, arranged to move the brake shoe away from the drum, thereby also operating the circuit closer and closing the circuit for the motor, means to lock the receptacle in mixing position, and means dependent upon the operation of the mixing device to control the operation of the locking device for the receptacle.
35. In a mixing device, a motor, a spindle actuated thereby, a support for the spindle, means to move the spindle longitudinally of its support while the motor is operating, means to rotatably connect the motor and spindle when said spindle reaches the end of its longitudinal stroke, a yieldable clutch mechanism to connect the spindle and its support, and means to cause the spindle to return to its normal position, by force imparted to it by the motor while operating, when the motor comes to rest.
40. In a mixing device, a rotatable spindle, a motor to move the spindle into a receptacle and rotate same while in the receptacle, and means to cause the mixing device to move out of the receptacle by centrifugal force.
45. In a mixing device, a motor having an armature, a mixing device carried by the armature and passing therethrough, a drum carried by the armature, a brake mechanism cooperating with the drum, a circuit for the motor, and a switch operable by the brake mechanism to open the circuit for the motor when the brake is applied.
50. In a mixing device, a motor, a drum carried thereby, brake shoes encircling said drum composed of separable members, means operable by the positioning of a receptacle, with respect to the mixing device, to separate said shoe-members, a circuit for the motor, and a switch operable by the separation of said shoe members to close the circuit for the motor.
55. In a mixing device, a motor, a brake mechanism therefor, a mixing device operable by the motor, means to lock a receptacle in position relative to the mixing device, a circuit for the motor and adjacent the locking means to simultaneously close the circuit for the motor and release the brake mechanism when a receptacle is placed in mixing position.
60. In a mixing device, a motor, a circuit therefor, a brake drum carried by the motor, a shoe normally engaging said drum, a circuit-closer adjacent the shoe included in said circuit, means carried by the shoe to operate circuit-closer, means operable by the
65. In a mixing device, a motor, a circuit therefor, a brake drum carried by the motor, a shoe normally engaging said drum, a circuit-closer adjacent the shoe included in said circuit, means carried by the shoe to operate
70. In a mixing device, a motor, a circuit therefor, a brake drum carried by the motor, a shoe normally engaging said drum, a circuit-closer adjacent the shoe included in said circuit, means carried by the shoe to operate the circuit-closer, means operable by the placing of a receptacle in mixing position, relative to the moving device, arranged to move the brake shoe away from the drum, thereby also operating the circuit closer and closing the circuit for the motor, means to lock the receptacle in mixing position.
75. In a mixing device, a motor, a circuit therefor, a brake drum carried by the motor, a shoe normally engaging said drum, a circuit-closer adjacent the shoe included in said circuit, means carried by the shoe to operate the circuit closer, means operable by the placing of a receptacle in mixing position, relative to the moving device, arranged to move the brake shoe away from the drum, thereby also operating the circuit closer and closing the circuit for the motor, means to lock the receptacle in mixing position.
80. In a mixing device, a motor, a circuit therefor, a brake drum carried by the motor, a shoe normally engaging said drum, a circuit-closer adjacent the shoe included in said circuit, means carried by the shoe to operate the circuit closer, means operable by the placing of a receptacle in mixing position, relative to the moving device, arranged to move the brake shoe away from the drum, thereby also operating the circuit closer and closing the circuit for the motor, means to lock the receptacle in mixing position.
85. In a mixing device, a motor, a circuit therefor, a brake drum carried by the motor, a shoe normally engaging said drum, a circuit-closer adjacent the shoe included in said circuit, means carried by the shoe to operate the circuit closer, means dependent upon the operation of the mixing device to control the operation of the locking device for the receptacle.
90. In a mixing device, a motor, a spindle actuated thereby, a support for the spindle, means to move the spindle longitudinally of its support while the motor is operating, means to rotatably connect the motor and spindle when said spindle reaches the end of its longitudinal stroke, a yieldable clutch mechanism to connect the spindle and its support, and means to cause the spindle to return to its normal position, by force imparted to it by the motor while operating, when the motor comes to rest.
95. In a mixing device, a rotatable spindle, a motor to move the spindle into a receptacle and rotate same while in the receptacle, and means to cause the mixing device to move out of the receptacle by centrifugal force.
100. In a mixing device, a rotatable spindle, a motor to move the spindle into a receptacle and rotate same while in the receptacle, and means to cause the mixing device to move out of the receptacle by centrifugal force.
105. In a mixing device, a motor having an armature, a mixing device carried by the armature and passing therethrough, a drum carried by the armature, a brake mechanism cooperating with the drum, a circuit for the motor, and a switch operable by the brake mechanism to open the circuit for the motor when the brake is applied.
110. In a mixing device, a motor, a drum carried thereby, brake shoes encircling said drum composed of separable members, means operable by the positioning of a receptacle, with respect to the mixing device, to separate said shoe-members, a circuit for the motor, and a switch operable by the separation of said shoe members to close the circuit for the motor.
115. In a mixing device, a motor, a drum carried thereby, brake shoes encircling said drum composed of separable members, means operable by the positioning of a receptacle, with respect to the mixing device, to separate said shoe-members, a circuit for the motor, and a switch operable by the separation of said shoe members to close the circuit for the motor.
120. In a mixing device, a motor, a brake mechanism therefor, a mixing device operable by the motor, means to lock a receptacle in position relative to the mixing device, a circuit for the motor and adjacent the locking means to simultaneously close the circuit for the motor and release the brake mechanism when a receptacle is placed in mixing position.
125. In a mixing device, a motor, a brake mechanism therefor, a mixing device operable by the motor, means to lock a receptacle in position relative to the mixing device, a circuit for the motor and adjacent the locking means to simultaneously close the circuit for the motor and release the brake mechanism when a receptacle is placed in mixing position.
130. In a mixing device, a rotatable sup-

- port, a mixing element carried by the support and movable into and out of a receptacle, a locking element to engage the receptacle when said receptacle is positioned relative to the mixing element, while the mixing element is positioned exteriorly of a receptacle, and means to lock the locking element against operation after the mixing element has entered a receptacle.
17. In a mixing device, a rotatable support, a mixing element carried by the support and movable into and out of a receptacle, a locking element to engage the receptacle when said receptacle is positioned relative to the mixing element, while the mixing element is positioned exteriorly of a receptacle, and means to lock the locking element against operation after the mixing element has entered a receptacle, arranged to again release the locking element when said mixing element is again moved to a position exteriorly of the receptacle.
18. In a mixing device, a motor, a circuit therefor, a switch included in said circuit, a mixing device operable by the motor and movable into and out of a receptacle, a locking element to engage a receptacle, while the mixing element is positioned exteriorly of a receptacle, means to lock the locking element against operation after the mixing element has entered a receptacle, and means adjacent the locking element for the receptacle to control the circuit for the motor.
19. In a mixing device, a motor, a circuit therefor, a switch included in said circuit, a mixing device operable by the motor and movable into and out of a receptacle, a locking element to engage a receptacle, while the mixing element is positioned exteriorly of a receptacle, means to lock the locking element against operation after the mixing element has entered a receptacle, means adjacent the
- locking element for the receptacle to control the circuit for the motor, and a brake mechanism for the motor operable by the circuit controlling means.
20. In a mixing device, a rotatable support, a threaded spindle carried thereby and movable longitudinally of the support, means carried by the support to engage the threads on the spindle, means carried by the support to cause same to lag whereby said spindle will be moved longitudinally of the carrier, in one direction, when the carrier is rotated, said spindle being arranged to rotate with the carrier, without longitudinal movement on the part of the spindle, when said carrier reaches the end of its longitudinal movement, and a brake mechanism to stop the rotation of the carrier whereby the spindle will move longitudinally of its carrier by the force imparted to it while the carrier is rotating.
21. In a mixing device, a motor, a mixing element operated thereby, a circuit therefor, a switch included in said circuit, a stop to prevent withdrawal of a receptacle while the mixing device is operating therein, means operated by the movement of the receptacle into mixing position to operate the switch to close the motor circuit, said stop being arranged to permit sufficient movement of the receptacle to permit the switch operating means to operate to open the circuit for the motor after a mixing operation, the releasing of the stop to allow withdrawal of the receptacle being controlled by the movement of the mixing element to a position exteriorly of the receptacle.

In testimony whereof I hereunto affix my signature.

THEODORE A. WOLTERS.
